UNITED STATES PATENT OFFICE

153,893

DESIGN FOR A COMBINED WASHING
MACHINE AND WRINGER

Jack Morgan, Chicago, Ill., assignor to Automatic
Washer Company, Newton, Iowa, a corporation
of Delaware

Application May 3, 1947, Serial No. 138,796

Term of patent 14 years

(Cl. D49—1)

To all whom it may concern:

Be it known that I, Jack Morgan, a citizen of the United States, residing at Chicago, in the county of Cook and State of Illinois, have invented a new, original, and ornamental Design for a Combined Washing Machine and Wringer, of which the following is a specification, reference being had to the accompanying drawing, constituting a part hereof.

Fig. 1 is a front elevational view of a combined washing machine and wringer embodying my new design with the wringer in sunken position within the tub and the cover in closed position on the machine;

Fig. 2 is a top plan view of Fig. 1;

Fig. 3 is a front elevation of the combined washing machine and wringer, with the wringer in elevated position for use; and

Fig. 4 is a top plan view of Fig. 3.

The characteristic features of my design for the combined washing machine and wringer disclosed reside in the annular disc-like portion on the upper front and in the top cover member

having the configuration and arrangement shown. The sides of the machine are substantially plain and present no particular design.

I claim:

The ornamental design for a combined washing machine and wringer, substantially as shown and described.

JACK MORGAN.
